(57) **CLAIM**

The ornamental design for a hot lid holder with drip pan, as shown and described.

DESCRIPTION

FIG. 1 is a perspective view of a hot lid holder with drip pan embodying the design of the present invention. The broken line showing of environmental structure is for illustrative purposes only and forms no part of the claimed design.

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.
